United States Patent Office.

TRUMAN P. KEELER, OF WORCESTER, MASSACHUSETTS.

Letters Patent No. 78,291, dated May 26, 1868.

IMPROVED ADJUSTABLE HAMMER AND DROP.

The Schedule referred to in these Letters Patent and making part of the same.

KNOW ALL MEN BY THESE PRESENTS:

That I, TRUMAN P. KEELER, of the city and county of Worcester, and Commonwealth of Massachusetts, have invented certain new and useful Improvements in Combined Adjustable Hammers and Drops; and I do hereby declare that the following is a full, clear, and exact description of the same, reference being had to the accompanying drawings forming a part of this specification, in which—

Figure 1 represents a side view of my improved trip-hammer and drop.

Figure 2 represents a front view of the same, and

Figure 3 represents a longitudinal central section on line A B, fig. 2.

To enable those skilled in the art to which my invention belongs to make and use the same, I will proceed to describe it more in detail.

My present improvements have for their object the production of a hammer that can be readily adjusted to strike with a varying force, and which can also be adjusted to be used as a drop.

In the drawings, A is the base of the machine, from which rise the two side-pieces B B.

The front parts B' B' of the side-pieces extend up higher than the rear parts B'' B''. Upon the latter are fitted the boxes or bearings a a of the main shaft A', upon which are mounted the varying or different-sized cams C C' C''.

The cam-shaft A' is fitted to slide easily in a longitudinal direction, to bring either of the cams under the arm D, which extends back from the hammer D', which is fitted to work up and down between proper guides or ways b b, attached in any proper manner to the front parts B' B' of the side-pieces B B.

A triangular lever, e, is hinged at 1, the upright or forked end d of which extends up, and its pins i i enter a groove cut in the shaft A', as indicated in red dotted lines in fig. 3, whereby, when the horizontal part e which extends out through the side of the frame, as shown at f, in fig. 2, is depressed or elevated, shaft A' and its cams will be moved one way or the other, as the case may be.

Upon the outside of the frame, the lower end of the connecting-piece E is pivoted to lever e, while the upper end of the same connection is pivoted to the crank-arm E' of the shaft E'', which is supported and turns in boxes or bearings, fastened to the upper ends of the parts B' B'.

Fastened to shaft E'' is the stop-block F, having, in this instance, two notches F' F''.

Rubber bunters g are inserted in the faces 2, 3, and 4 of the stop-block F, for a purpose hereafter named.

To one of the side-pieces B is fastened, by a hinge or pivot-joint, a stop-piece, G, having two notches, 5 and 6. When lever e is depressed, so as to be held down by the notch 5 of the stop-piece G, as shown in the drawings, the stop-block F will be drawn in, so that the rubber bunter g in the face 3 will be in the proper position to receive and arrest the hammer D', as it is thrown up by the cam C', which will be moved under the arm D, when lever e is in the position shown in the drawings.

When lever e is depressed, so as to be caught and held down by the notch 6 in the stop-piece G, cam C'' is moved under the arm D, and the stop-block F is swung out, so as to allow the hammer to rise until arrested by the bunter g in the face 4, while, when the stop-piece G is drawn out, so as to allow lever e to be drawn up to its highest point by the spring h, the small cam C is moved under the arm D, and stop-block F is moved so as to bring the bunter g, in the face 2, into position to receive and arrest the bound of the hammer.

It will be observed that the operator can very easily and quickly adjust the hammer to give a long or short stroke, and, consequently, a hard or soft blow.

Shaft A' is to be driven by a pulley, upon which runs a loose belt, to be tightened by a binding-pulley, when the hammer is to be put into operation, and loosened when the hammer is to be stopped.

The binder is to be combined with the foot-treadle H, so that when the latter is depressed, as shown in red lines, fig. 3, the hammer will be put into operation, and when the foot is removed, the hammer will stop, the treadle being elevated by the springs K K, or the weight of the binder-pulley.

I have now described how my hammer can be adjusted to give a hard or soft blow, and I will now explain how it can be adjusted so as to act as a drop, when either of the cams is moved under the arm D.

To the side arms *m m* of the treadle H are hinged or pivoted the lower ends of the connections I I', to which the ends of the stop-bar J are fastened by the screws *n n*. The ends of the stop-bar work up and down in vertical slots in the side-pieces B B.

The stop-bar J, it will be seen, will rise and fall with the treadle H, and when up, as shown in dark lines in the drawings, will be struck by the projection *o*, on the outer side of the cam C'', thereby stopping the cams while the catch *p* is turned so as to catch into one of the notches *q* in the hammer D', thereby retaining the hammer in the elevated position shown in fig. 3.

As the journal of the catch *p* passes through the side-piece B, and its arm *s* is connected to the upper end of the connection I, as shown at *t*, the catch is turned back, when the treadle H is depressed, all as shown in red lines, fig. 3.

As soon as treadle H is depressed, as described, the hammer falls, and the stop-bar J being depressed also, the cams are put in motion again, and acting upon the arm D, the hammer is elevated, but as the foot of the operator is immediately withdrawn from the treadle, it rises, the cams are stopped and the hammer caught again, ready to be dropped at the pleasure of the attendant.

When it is desired to run the hammer constantly, the attendant keeps his foot upon the treadle H.

To guard against the cams being shifted while the hammer is being raised, the cams C C' are provided with fins *u*, upon their inner sides, as indicated by dotted lines, fig. 1, and full lines, fig. 3.

The fins *u* prevent the cams being slipped laterally, until the point of the arm D has been passed, when they can be moved, even though the cams are still in operation.

If preferred, in any case, a spring, W, may be fastened to the top of the arm D, to aid in stopping and easing the bound of the hammer as it is raised.

It is apparent that many of the parts above described may be modified without departing from the principle of my invention.

Having described my improved combined adjustable hammer and drop, what I claim as new and of my invention, and desire to secure by Letters Patent, is—

1. The combination, with the hammer, of an adjustable stop-block, F, and mechanism for operating the same, substantially as and for the purposes set forth.
2. The combination, with the hammer, of the stop-block, for checking its upward movement, the cams and cam-shaft, for operating the hammer, and the lever *e*, connected with and arranged to adjust both the cams and the stop-block, substantially in the manner and for the purposes shown and set forth.
3. The combination, with the adjusting-lever, connected with the cam-shaft and stop-block, as specified, of the stop-piece G, or its equivalent, substantially as and for the purposes set forth.
4. The stop-bar J, and treadle, or equivalent means for operating the same, in combination with the hammer-actuating cams, under the arrangement and for operation as shown and set forth.
5. The combination, with the hammer, and cams for operating the same, of the stops *p* and J, connected with and actuated by the treadle H, in the manner and for the purposes herein shown and specified.
6. The combination and arrangement, with the hammer, its actuating-cams, and the stop-block for checking its upward movement, of the mechanisms herein described for adjusting said cams and stop-block, and for arresting and holding the said cams and hammer, whereby the machine may be used either as a hammer or as a drop, and the stroke of the hammer, in either case, may be varied, substantially as shown and set forth.

TRUMAN P. KEELER.
